No. 759,103.

Patented May 3, 1904.

UNITED STATES PATENT OFFICE.

JUDSON K. HEIKES, OF ST. LOUIS, MISSOURI.

DETERGENT COMPOUND.

SPECIFICATION forming part of Letters Patent No. 759,103, dated May 3, 1904.

Application filed November 14, 1903. Serial No. 181,232. (No specimens.)

To all whom it may concern:

Be it known that I, JUDSON K. HEIKES, a citizen of the United States, residing at St. Louis, State of Missouri, have invented a new 5 and useful detergent compound to be used for cleansing and bleaching clothes, washing utensils and floors, and for all purposes requiring the use of a cheap and convenient detergent, of which the following is a specification.

10 My composition is composed of the following ingredients combined in the proportions stated, viz: cotton-seed oil, four ounces; coal-oil, one hundred and four ounces; linseed-oil, three ounces; light lubricating-oil of mineral 15 origin, five ounces; olive-oil, two ounces; oil of sassafras, eight ounces; oleum citronella, four ounces, and one-fourth of a pound of alkanet-root. Mix thoroughly by agitation.

Directions for using: Add clothes to a tub 20 of clear water, then add soap enough to form suds, and heat the water sufficiently. When hot, add eight ounces of the compound and agitate the clothes twenty-five minutes, keep-

ing the water hot by steam injection or otherwise, and then discharge; then give the clothes 25 a hot rinse for ten minutes and discharge; then scour from five to eight minutes and discharge; then cold-rinse for five minutes and blue as usual. Water similarly prepared cleanses utensils, floors, &c. 30

What I claim, and desire to secure by Letters Patent of the United States, is—

The herein-described detergent composition consisting of linseed-oil, coal-oil, cotton-seed oil, light lubricating-oil of mineral origin, 35 olive-oil, oil of sassafras, oleum citronella and alkanet-root in substantially the proportions given.

In testimony whereof I have signed my name to this specification in the presence of two witnesses. 40

JUDSON K. HEIKES.

Witnesses:

PHIL CHEW,
J. E. DUST.
